COMBINED ROBE AND BAG

Boyd O. Sartell, Faribault, Minn., assignor to Faribault Woolen Mill Company, Faribault, Minn., a corporation of Minnesota

Application April 21, 1955, Serial No. 502,827

3 Claims. (Cl. 2—69.5)

This invention relates to a combined robe and bag. The invention is more particularly concerned with a combined robe and bag for protecting a person against the weather elements, especially at outdoor sports events such as football games and the like, whereat the spectators are usually in a sitting position and accordingly cannot maintain body warmth through physical movement thereof.

A primary feature of the invention is a robe together with a panel secured to the robe adjacent one edge thereof and midway of opposed adjacent edges and which provides, with the opposed portion of the robe, a bag or pouch for the reception of a person's feet, and the portions of the robe at opposite sides of said panel adapted to be wrapped about the body of the person.

A further feature of the invention is a body-protecting robe of substantial dimensions, and a rectangular panel of relatively small dimensions disposed adjacent one edge of the robe and intermediate opposed edges thereof, the panel being secured to the robe about three of its four edges, whereby same provides, with the opposed robe portion, a bag into which the remaining portion of the robe is disposable for transportation of the combined robe and bag.

A still further feature of the invention is a combined robe and bag of the character above referred to wherein the bag is provided with draw strings adapting same for concealment of the robe as well as for convenient carrying.

Other features and advantages of the invention will become apparent in the course of the following detailed description, taken in connection with the accompanying drawings, wherein

Figure 1 is a plan view of the combined robe and bag in a position for use.

Fig. 2 is a transverse sectional view as observed in the plane of line 2—2 on Fig. 1.

Fig. 3 is a transverse sectional view on a substantially enlarged scale as observed in the plane of line 3—3 on Fig. 1.

Fig. 4 is a side elevational view of the combined robe and bag in a position for transportation thereof.

Fig. 5 is a view similar to Fig. 4 but from the opposite side thereof and wherein the draw strings are drawn up.

Referring now in detail to the drawing, 10 designates a robe which is preferably square and approximately fifty inches by fifty inches in dimensions. The robe 10 is preferably of one hundred percent wool for maximum insulating qualities, but it is to be understood that any other suitable material may be used.

A relatively narrow rectangular strip of fabric 11 is disposed on one face of the robe with one of the longer edges thereof coinciding with an edge of the robe, as is particularly indicated in Fig. 3. A substantially square panel of fabric 12 is disposed over the strip 11 with one edge thereof coinciding with the said coinciding edges of the strip and robe and the adjacent opposed edges of the panel coincide with the opposite ends of the strip.

2

A beaded welt 13 is disposed between the aligned edges of strip 11 and panel 12 as well as between said opposed edges of the panel and the robe 10, and the said edge together with the welt strip are secured to the robe 10 by 5 lines of stitching 14. The opposite longer edge of the strip 11 is secured to the robe by a line of stitching 15, and the bead 16 of the beaded welt extends along all the stitched edges of the strip and panel as is apparent from Fig. 4.

10 A folded-over fabric strip 17 is stitched to the robe 10 as at 18, and a similar folded-over fabric strip 19 is stitched to the free edge of panel 12 as at 20.

From the above disclosure, it will be apparent that a portion 10^a of the robe 10 and the panel 12 provide a bag, and in order to close such bag, as will later be referred to, the strips 17 and 19 are provided with aligned eyelets 21 in which are movably disposed draw strings 22.

The adjacent faces of strip 11 and panel 12 in the operative position indicated in Fig. 3 are preferably rubberized to render same waterproof, but it is to be understood that any other suitable material may be used.

With the combined robe and bag in the position of Fig. 1 a person's feet may be inserted into the bag, after which the opposed portions 10^b of the robe 10 may be folded 25 over substantially on the lines L into overlying relation to the person's body.

The bag may, however, under some circumstances, be used as a hood, and in which instance the robe would serve as a cape.

30 When it is desired to package the robe for storage or transportation thereof, the major portion of the robe as is shown in Fig. 1 is folded and disposed within the bag provided by the panel 12 and portion 10^a of the robe. Such disposition of the robe may be accomplished by 35 folding the robe on lines transversely thereto and thereafter turning the strip 11 and panel 12 to a position in encompassing relation to the folded bag portion. As an alternative procedure, the bag may be turned with a resulting drawing of the lateral portions of the robe thereinto, and thereafter the protruding robe portion folded on lines L as well as lines perpendicular thereto and then moved into the bag.

40 It is to be observed that the rubberized faces of strip 11 and panel 12 are disposed outwardly in the bagged condition of the robe.

The robe may be and preferably is of an ornamental design and when same is folded into packaged condition the panel 11 and portion 10^a of the robe will provide a pleasing appearance, as will be observed from Fig. 4.

50 For transporting the bagged robe, the draw strings 22 are pulled with a resulting collapsing of the mouth of the bag, as indicated in Fig. 5.

It is to be particularly observed that in the operative position of the robe, as indicated in Fig. 1, the bag bottom coincides with one edge of the robe, whereby upon 55 insertion of a person's feet into the bag the opposite side portions of the robe may be folded over the person's body in the absence of any portions protruding below the bag and becoming soiled, wetted, or damaged by contact with the ground. Furthermore, such coincidence of the bag bottom and an edge of the robe makes it possible to turn the bag for disposition of the robe therein, and when the robe is in bagged condition a convenient and 60 neat package is provided, wherein one side thereof is formed of the rubberized fabric panel 12 and the opposite side thereof is formed of the rubberized fabric strip 11 and a portion of the robe with the bead 16 extending along the bottom and opposite sides of the packaging bag for further enhancing the appearance thereof.

65 While I have disclosed my invention in accordance with a single specific preferred embodiment thereof, such is to

be understood as illustrative only and not restrictive, the scope of the invention being defined in the subjoined claims.

What I claim and desire to secure by U. S. Letters Patent is:

1. A combined robe and bag comprising a rectangular robe, a rectangular panel of smaller area than said robe disposed upon one side of said robe and having one edge thereof coinciding with one edge of the robe, and a pair of opposed parallel edges thereof being in right angular relation to said first edge and in spaced parallel relation to opposed edges of the robe which are in right angular relation to the first edge thereof, the said three edges of the panel being secured to the robe and the fourth edge thereof which is in spaced parallel relation to the first edge thereof being free of the robe, thereby providing a pocket for the reception of a user's feet, and the portions of the robe at opposite sides of the pocket being inwardly foldable over the body of the user, the coincidence of the bottom of the bag with one edge of the robe facilitating turning of the bag and the positioning of the robe therein for transportation or storage thereof, together with a relatively narrow strip disposed between said robe and said panel and having one edge thereof coinciding with said first edges of said robe and said panel, the opposite edge of said strip being secured to said robe, and the opposite ends of said strip coinciding with said pair of opposed edges of said panel and being secured there-

with to said robe, and said panel and said strip being of waterproof fabric, for the purpose set forth.

2. The structure according to claim 1, together with a strip folded over the free edge of said panel and secured thereto, a similar strip secured to said robe opposite said first strip, aligned eyelets in said strips, and draw strings extending through said eyelets.

3. The structure according to claim 1, together with a 10 welt having a marginal bead disposed between said robe and the secured edges of said panel and said strip, and wherein said bead is disposed internally of the bag in the position of use of said robe, and which is disposed externally of the bag in the robe-encompassing position thereof.
